INVENTOR.

William E. Bowers,

BY

Geo. P. Kimmel. ATTORNEY.

UNITED STATES PATENT OFFICE.

WILLIAM E. BOWERS, OF BALTIMORE, MARYLAND.

PORTABLE COMBINED INK PAD AND SUPPORT.

Application filed June 18, 1925. Serial No. 38,021.

To all whom it may concern:

Be it known that I, WILLIAM E. BOWERS, a citizen of the United States, residing in the city of Baltimore and State of Maryland, have invented certain new and useful Improvements in Portable Combined Ink Pads and Supports, of which the following is a specification.

This invention relates to a portable combined ink pad and support designed primarily for use of postal employees in the stamping of mail matter, but it is to be understood that a device, in accordance with this invention, can be employed for any usages for which it is found applicable, and the invention has for its object to provide, in a manner as hereinafter set forth, a combined ink pad and support capable of being removably mounted in fixed position in convenient reach of a person, more particularly in fixed position on the top of the side or end wall of a receptacle containing a large number of parcels, such as mail matter, whereby the convenient stamping of the parcels can be had as well as further providing for an expeditious stamping operation.

Further objects of the invention are to provide, in a manner as hereinafter set forth, a portable combined ink pad and support, which is simple in its construction and arrangement, strong, durable, compact, thoroughly efficient in its use, conveniently mounted in fixed position, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claim hereunto appended.

In the drawings wherein like reference characters denote corresponding parts throughout the several views:

Figure 1 is a side elevation of a portable combined ink pad and support and further illustrating the arrangement of the same in fixed position with one of the walls of the receptacle, the latter being shown in dotted lines.

Figure 2 is a front elevation of the portable combined ink pad and support. 55

Figure 3 is a sectional plan.

Figure 4 is a side elevation, partly in longitudinal section.

A portable combined ink pad and support, in accordance with this invention, includes an ink pad carrier of any suitable contour and including means for receiving and holding the ink pad which also may be of any suitable contour, preferably the carrier 1, 65 is in the form of a rectangular member provided with a circular pocket 2 for receiving a circular pad 3. The depth of the pocket 2 relative to the height of the pad 3 is such that the latter will permanently project 70 above the upper face of the carrier 1. Each outer corner of the carrier 1 is rounded, as at 4, and the carrier 1 has the upper portion of its outer end edge and a part of each side edge bevelled, as at 5, 6 respectively. The inner end of the carrier 1 is squared, as at 7. The length, width and thickness of the carrier 1 can be as desired, and the pocket 2 is disposed centrally of the upper 75 face thereof and also can be of any desired diameter. 80

Secured against the rear end of the carrier 1 is a rectangular retaining member 8 of a greater height than the height of the carrier 1. The member 8 is flush with the upper face of the carrier 1 and depends a substantial distance below the lower face of said carrier. The ends of the member 8 are flush with the sides of the carrier 1. The member 8 is secured to the carrier 1 through the medium of a pair of outer holdfast devices 9 and an inner holdfast device 10, which is of less length than either of the holdfast devices 9. The holdfast devices 9 and 10 are in the form of screws and the heads 11 thereof are countersunk in the rear face of the member 8. The holdfast devices 9 are arranged above the holdfast device 10 and each of said holdfast devices 9 is positioned 90 at a point nearer an end of the member 8 than the center thereof. The holdfast device 10 is positioned centrally of the member 8 and when in position extend to a point in close proximity to the pocket 2. The arranging of the holdfast devices 9 and 10 in the manner as stated fixedly secured the retaining member 8 to the carrier 1 so that said member 8 cannot become disconnected. 95 100 105

from the carrier 1 under ordinary conditions.

Mortised in the lower face of the carrier 1, centrally thereof, and disposed lengthwise of the carrier is a substantially rectangular head 12 of a combined supporting and locking member which coacts with the retaining member for the purpose of removably securing the carrier 1 in fixed position 10 to a support, and said support by way of example is illustrated as one of the walls 13 of a container. The combined supporting and locking member further includes an inwardly disposed arcuate extension 14, 15 which depends from the head 12. The rear end of the head 12 is bevelled, as at 15, and said end opposes the lower portion of the retaining member 8. The bevel 15 inclines upwardly and forwardly with respect to the 20 forward face of the retaining member 8. The free end of the extension 14 is also bevelled, as at 16, and the said bevel 16 forms a continuation of the plane of the bevel 15. The bevelled inner end of the 25 head 12, in connection with the depending portion of the retaining member 8, provides an opening 17, which gradually increases in width upwardly and in which the upper portion of the wall 13 is forced to bind the 30 same against the support whereby the latter is retained in position, and when the top of the wall is in such position the bevelled lower end of the extension 14 abuts against the same and sets up a bracing action to 35 maintain the carrier 1 in the position shown in Figure 1.

The head 12 of the combined supporting and locking member is secured in the lower face of the carrier 1 by a plurality of 40 vertically disposed hold-fast devices 18, which are in the form of screws and have their heads 15 countersunk in the bottom of the pocket 2.

When the combined ink pad and support 45 is detachably mounted in the position as shown in Figure 1, the carrier 1 is maintained in a position at right angles to the

retaining member 8 through the medium of the combined supporting and locking member abutting against the outer face of the 50 wall 13 of the container. The device can be quickly removed from set position and mounted in any other convenient position within the reach of the operator, and it is obvious that in connection with the stamping of mail matter, particularly parcel post packages, as the ink pad and support can be removably mounted in fixed position upon any of the walls of the container for the parcels, the stamping operation can be 60 conveniently had as well as expedited.

It is thought that the many advantages of a portable combined ink pad and support in accordance with this invention, can be readily understood, and although the preferred embodiment of the invention is as illustrated and described, yet it is to be understood that changes in the details of construction can be had which will fall within the scope of the invention as claimed. 70

What I claim is:—

A support for an ink pad for mounting on the top edge of a receptacle comprising a substantially rectangular imperforate carrier having its upper face formed with a 75 shallow pocket to receive the ink pad, a rectangular retaining member having its outer face positioned against and depending from the rear edge of said carrier, means for securing the upper portion of said member to the carrier, a combined supporting and locking member consisting of a head and an extension depending therefrom, said head mortised in the lower face of the carrier intermediate the ends of the longitudinal median thereof and having its rear edge spaced and inclining from the forward face of said member, said edge inclining forwardly from the bottom of the head, and means for detachably securing the head and carrier together. 80

In testimony whereof, I affix my signature hereto.

WILLIAM E. BOWERS.
